UNITED STATES PATENT OFFICE.

JAMES H. RAND, OF NEWTON, MASSACHUSETTS.

SELF-INDEXING STORAGE DEVICE.

1,296,851.

Specification of Letters Patent. Patented Mar. 11, 1919.

Application filed October 29, 1917. Serial No. 199,020.

To all whom it may concern:

Be it known that I, JAMES H. RAND, a citizen of the United States of America, and resident of Newton, in the county of Middlesex and State of Massachusetts, have invented new and useful Improvements in Self-Indexing Storage Devices, of which the following is a specification.

This invention relates to self-indexing storage systems adapted to maintain a series of unit containers for flat objects such as stencils, card-plate, addressing machines, name-plates or the like, in a suitable frame, one above another in over-lapping and spaced relation, so that a part of each unit of the system is constantly visible. Indexes in which overlapping cards or the like are supported by a bar or strip to which the card is secured at one edge, said strip providing laterally extending projections at each side removably secured in inwardly-facing guide channels of a suitable panel or frame, are familiar in the prior art, which also contains instances of pockets or containers adapted to hold a card or the like. The invention provides a device of this general character which shall be adapted to hold for convenient access and in over-lapping relation a series of relatively flat objects of the class above mentioned, principal objects being to provide for compact storage of and protective covering for a large number of such objects; for the display of an identifying label, (such as an imprint from a stencil) which will denote the object in each container; and to provide means by which the absence of the stored object from a container not itself absent from the series will be signaled. Other objects are to provide durable and efficient constructions adapted to the general purposes mentioned.

In the accompanying drawings, which illustrate one preferred embodiment of my invention only,

Figure 1 is a face view of a suitable frame and series of containers;

Fig. 2 is a perspective of a primary supporting bar forming a part of each unit;

Fig. 3 is a section on line 3-3 of Fig. 1; and

Fig. 4 is a detail perspective of a secondary supporting bar.

The panel or frame A comprising the inwardly channeled members A', A', may be of any desired or suitable construction, for instance being made as a flat rectangular

frame of metal adapted to be hinged on the vertical line on one of the channel members A', hung on a wall, or otherwise adapted to be vertically positioned to be displayed as a whole.

Preferably rectangular bars or strips 1, of a length to fit within the channels A', A', and to slide freely therein are provided to serve as primary supports for the containers or storage pockets B, Fig. 3. The bars 1 are of material adapted to be flexed to enter or remove the ends of a bar from the channels A', a preferred material being well seasoned wood. The vertical dimensions of the bars are such as to space their centers apart, when they rest against each other, by the desired vertical width of the label or display indication on the bottom of the pockets B.

The pockets B may be made of strong cardboard or the like, and preferably as shown comprise a rectangular blank 3 having a short upper forward flap 4 and a lower forward flap 5, the fold 3, 4, being open at its sides, and the fold 3, 5, constituting the pocket for the stencil or the like, also preferably being open at the lateral margins, although these margins may be suitably secured together if desired. Flap 4 is permanently fastened, as by wire staples 6, the fold 3, 4, being adapted to receive and hinge upon a secondary support 8 shorter than the space between channels A', preferably made as a wire hinge member, bent upon itself at its ends 9, and so adapted to be held in the slots 2 of the bars 1, from which it can be removed, along with pocket B, by flexing the bar 1 when it is free from the channels A'. The ends 9 of the secondary supports 8 abut against the channels to centrally space the bars 1 and pockets B.

The front wall 5 of the pocket 3, 5, is perforated at 10 to display the back wall of the pocket when the pocket is empty. Preferably the inside of the back wall opposite the window or opening 10 is locally colored at 11 differently from the front face of flap 5, so that absence of the object 12 usually contained in the pocket will be signaled by the appearance of the colored signal 11.

The exposed bottom part of the flap 5 is provided with a supplementary pocket adapted to hold a slip 16 identifying the contents of the pocket B of which it forms a part. For instance, a strip 14 of a preferably transparent substance, such as celluloid,

may be attached at its lower or both upper and lower margins, as shown, to the strip 5, as by wire staples 15. Strip 14 may cover the signal window 10, and is adapted to receive between itself and the flap 5 the strip or label 16 having thereon an imprint or other identifying mark corresponding to the stencil or other object to be placed in the pocket B. The lateral width of the pockets 10 B may be less than the space between channels A', as shown.

In use, absence of the object contained from any of the containers is indicated by appearance of signal 11. Each of the pockets 15 is readily and instantly accessible for removal or replacement of its stencil or other stored object, the constantly visible labels 16 permitting rapid finding of the desired pocket. Alphabetical or other order for a 20 changing series of the objects is permitted to be maintained by the adaptability of the bars 1 and their attached pockets to be removed and replaced; the secondary supports 8 enabling any container to be exposed for 25 access to its contents by lifting the series of containers above it.

I claim:—

1. A self-indexing storage device having a channelled frame, supporting and spacing 30 members therein, and a series of containers suspended from the supporting and spacing members, each of said containers having a supplementary pocket adapted to be exposed when the containers are in overlapping relation.

2. A self-indexing storage device having a channelled frame, primary supporting and spacing members therein, secondary supporting members carried by said primary members, and a series of containers suspended 40 from said secondary members, each of said containers having a supplementary pocket adapted to be exposed when the containers are in overlapping relation.

45 3. A self-indexing storage device having therein a channelled frame, primary supporting members held in the channels in said frame, a series of containers suspended from said supporting members and spaced apart

thereby, whereby to hold in overlapped relation and expose the bottoms of said containers, a signal device at one side of the exposed portion adapted to be displayed when the container is empty, and means for supporting an identifying label at another part 55 of the exposed area.

4. Container supporting means for a self-indexing storage device consisting of a rectangular wooden bar having slots at its ends, and having a wire secondary support upon 60 which the container can be hung held on the bar by engagement of hooked ends of the wire with the slots in the bar.

5. A unit for self-indexing storage devices comprising a container, a wire support included in a fold of the container, said support having hooked ends, and a primary support having slotted ends adapted to engage the hooked ends of said wire support. 65

6. A self-indexing storage device comprising a channelled frame, primary supporting and spacing bars adapted to be flexed for engagement and disengagement with channels in said frame, slots in the end of said bars, secondary supports having ends adapted to be received in and held by said slots, whereby laterally to position said primary and secondary supporting means, and containers suspended from said secondary supports. 70

7. A cardboard container for self-indexing storage systems comprising a pocket-forming fold, a supporting fold, a visible signal adapted to be displayed when the container is empty, and a supplementary 85 pocket attached to said pocket-forming fold.

8. A cardboard container for self-indexing storage systems comprising a pocket-forming fold, a supporting fold, a visible signal adapted to be displayed when the container is empty, and a supplementary pocket attached to said pocket-forming fold having 90 a transparent wall adapted to display a label.

Signed by me at Boston, Massachusetts, 95 this twenty-second day of October, 1917.

JAMES H. RAND.
